(57) **CLAIM**

The ornamental design for a pet treat, as shown and described.

DESCRIPTION

FIG. 1 is a perspective view of a design for a pet treat, illustrating a front, side, and bottom view;

FIG. 2 is a front elevation view of the pet treat shown in FIG. 1;

FIG. 3 is a rear elevation view of the pet treat shown in FIG. 1;

FIG. 4 is a top plan view of the pet treat shown in FIG. 1;

FIG. 5 is a bottom plan view of the pet treat shown in FIG. 1;

FIG. 6 is a side elevation view of the pet treat shown in FIG. 1;

FIG. 7 is another side elevation view of the pet treat opposite the side elevation view shown in FIG. 6;

FIG. 8 is a perspective view of another design for a pet treat, illustrating a front, side, and bottom view;

FIG. 9 is a front elevation view of the pet treat shown in FIG. 8;

FIG. 10 is a rear elevation view of the pet treat shown in FIG. 8;

FIG. 11 is a top plan view of the pet treat shown in FIG. 8;

FIG. 12 is a bottom plan view of the pet treat shown in FIG. 8;

FIG. 13 is a side elevation view of the pet treat shown in FIG. 8;

FIG. 14 is another side elevation view of the pet treat opposite the side elevation view shown in FIG. 13;

FIG. 15 is a perspective view of a further design of a pet treat, illustrating a front, side, and bottom view;

FIG. 16 is a front elevation view of the pet treat shown in FIG. 15;

FIG. 17 is a rear elevation view of the pet treat shown in FIG. 15;

FIG. 18 is a top plan view of the pet treat shown in FIG. 15;

FIG. 19 is a bottom plan view of the pet treat shown in FIG. 15;

FIG. 20 is a side elevation view of the pet treat shown in FIG. 15;

FIG. 21 is another side elevation view of the pet treat opposite the side elevation view shown in FIG. 20;

FIG. 22 is a perspective view of yet another design of a pet treat, illustrating a front, side, and bottom view;

FIG. 23 is a front elevation view of the pet treat shown in FIG. 22;

FIG. 24 is rear elevation view of the pet treat shown in FIG. 22;

FIG. 25 is a top plan view of the pet treat shown in FIG. 22;

FIG. 26 is a bottom plan view of the pet treat shown in FIG. 22;
FIG. 27 is a side elevation view of the pet treat shown in FIG. 22;
FIG. 28 is another side elevation view of the pet treat opposite the side elevation view shown in FIG. 27;
FIG. 29 is a perspective view of yet a further design of a pet treat, illustrating a front, side, and bottom view;
FIG. 30 is a front elevation view of the pet treat shown in FIG. 29;
FIG. 31 is rear elevation view of the pet treat shown in FIG. 29;
FIG. 32 is a top plan view of the pet treat shown in FIG. 29;
FIG. 33 is a bottom plan view of the pet treat shown in FIG. 29;
FIG. 34 is a side elevation view of the pet treat shown in FIG. 29;
FIG. 35 is another side elevation view of the pet treat opposite the side elevation view shown in FIG. 34;
FIG. 36 is a perspective view of even another design for a pet treat, illustrating a front, side, and bottom view;
FIG. 37 is a front elevation view of the pet treat shown in FIG. 36;
FIG. 38 is a rear elevation view of the pet treat shown in FIG. 36;
FIG. 39 is a top plan view of the pet treat shown in FIG. 36;
FIG. 40 is a bottom plan view of the pet treat shown in FIG. 36;
FIG. 41 is a side elevation view of the pet treat shown in FIG. 36;

FIG. 42 is another side elevation view of the pet treat opposite the side elevation view shown in FIG. 41;
FIG. 43 is a perspective view of even a further design for a pet treat, illustrating a front, side, and bottom view;
FIG. 44 is a front elevation view of the pet treat shown in FIG. 43;
FIG. 45 is a rear elevation view of the pet treat shown in FIG. 43;
FIG. 46 is a top plan view of the pet treat shown in FIG. 43;
FIG. 47 is a bottom plan view of the pet treat shown in FIG. 43;
FIG. 48 is a side elevation view of the pet treat shown in FIG. 43;
FIG. 49 is another side elevation view of the pet treat opposite the side elevation view shown in FIG. 48;
FIG. 50 is a perspective view of yet even another design of a pet treat, illustrating a front, side, and bottom view;
FIG. 51 is a front elevation view of the pet treat shown in FIG. 50;
FIG. 52 is a rear elevation view of the pet treat shown in FIG. 50;
FIG. 53 is a top plan view of the pet treat shown in FIG. 50;
FIG. 54 is a bottom plan view of the pet treat shown in FIG. 50;
FIG. 55 is a side elevation view of the pet treat shown in FIG. 50; and,
FIG. 56 is another side elevation view of the pet treat opposite the side elevation view shown in FIG. 55.
